FLAP CLOSER AND STOP FOR SLIDE FASTENERS

Lester Feinstein, 3 Ruey Place, Plainview, N.Y.
Filed Aug. 6, 1962, Ser. No. 215,023
6 Claims. (Cl. 2—234)

This invention relates to slide fastener assemblies for garment, and in particular to the provision of a new and useful combined end enclosure and stop assembly for flexible tape-mounted edge fasteners.

The arrangement of the present invention is particularly suited for slider types of edge fasteners in common use for drawing together overlapping edge portions at the waist of a woman's dress or skirt, for example. Various arrangements have been devised in connection with the installation and use of slide fasteners for the purpose of limiting travel of the fastener slide so as to prevent disassembly thereof from the fastener rack teeth and also to prevent separation or opening of the slide fastener in response to an excessive pull applied to the fastener mounting tapes. Although the prior arrangements referred to have been successful in maintaining the slide fastener in its closed condition while preventing disassembly of the slider, they have not been as successful in preventing separation of the fastener mounting tapes from the garment material adjacent to the closure assembly at which location the maximum stress is applied to the tape stitching. Accordingly, it is a primary object of the present invention to provide a combined closure and stop assembly for use in connection with slide edge fasteners, which will not only effectively prevent disassembly and separation of the slide fastener itself, but will also cope with the excessive stress problem created when the confronting edge portions at the terminal end of the slide fastener are brought together in order to engage the hook and eye member of the closure assembly.

Another object of the present invention is to provide a combined closure and stop assembly which is of such novel construction and is so related installation-wise as to secure a neater appearance at the closed terminal end of the slide fastener.

In accordance with the foregoing objects, the combined closure and stop assembly features a novel hook member which is provided with a pair of projecting attachment lugs straddling the hook portion of the hook member and disposed in overlapping relation to the eye member in order to secure the hook member to the garment material independently of and in spaced relation to the flexible tape to which the hook member is otherwise secured. In this manner, a flatter and neater appearance is maintained adjacent to the closure portion of the garment and further, the stress applied to the tape stitching is relieved by the tacking of the attachment lugs directly to the garment material. It will, therefore, be obvious that the small additional labor involved in tacking the hook member to the garment material is well worth the resulting significant improvement in the durability and neatness of the slide fastener installation.

The invention from which other features and objects thereof will be readily apparent is fully described hereinafter with reference to the accompanying drawing illustrating a preferred embodiment in which:

FIGURE 1 is a partial front view of an exemplary garment installation of the invention with an overlapping flap of the garment broken away.

FIGURE 2 is a partial front view similar to that of FIGURE 1 illustrating the slide fastener in a fully closed condition.

2

FIGURE 3 is a sectional view taken through a plane indicated by section line 3—3 in FIGURE 2.

FIGURE 4 is a perspective view of the hook member of the closure and stop assembly.

Referring now to the drawing in detail, reference number 10 designates a garment, apparel or article of clothing having overlapping flap portions 12 and 14 to which a slide fastener assembly 16 is secured. The slide fastener assembly has associated therewith a pair of edge fastening tapes 18 and 20 respectively secured to the flap portions 12 and 14 by stitching 42 and 44. The tapes are provided with confronting bead portions 22 and 24 to which the fastener rack teeth 26 are secured and are adapted to be locked or opened by the slider 28 in a manner well known. The slider is accordingly provided with a pull tab 30.

It will be observed from FIGURE 1, that the uppermost rack teeth 26 are spaced from the combined closure and stop assembly generally referred to by reference numeral 32, so as to permit complete closing of the rack teeth before the slider 28 is disposed in abutting relation to the closure and stop assembly as shown in FIGURE 2.

The closure and stop assembly includes an eye member 34. The eye member has a pair of end portions 36 provided with bead clamping bifurcations 38 by means of which the eye member is secured in adjusted position to the flexible bead 24 of the tape 20, as more clearly seen in FIGURE 3. Bridging the end portions 36 is the hook engaging portion 46. The hook engaging portion is operative to tension the tape by engagement with the hook member 46 as shown in FIGURE 3.

The hook member 46 as shown in FIGURE 4 includes a flat portion 48 which is adapted to bridge the space between the tape 18 and the eye member. One end 52 of the flat portion 48 is provided with a pair of spaced prongs 54 which adapted to pierce the tape and be bent about the bead 22 in order to secure the hook member to the tape 18. Disposed opposite the prongs in alignment with the bridging portion of the eye member is the arcuate hook portion 56. Projecting from opposite sides of the hook portion in the same plane as the flat portion 48, are a pair of attachment lugs 58. When the hook portion 56 is engaged with the eye member, the attachment lugs will overlap the eye member. Disposed at the terminal end portions 60 of the attachment lugs are apertures 62 by means of which the lugs may be secured by tacking 64 to garment material beneath the flap portion 12. In this manner, the hook member will be secured to the garment material independently of its securing to the tape 18 also in spaced relation to the stitching 42 on the opposite tape 14 on the side remote from tape 18. Furthermore, the use of a pair of spaced lugs will hold the garment material in taut condition over the closure stop assembly as more clearly seen in FIGURES 2 and 3.

From the foregoing description, the arrangement and utility of the invention will be apparent as well as its advantageous attributes. It will be appreciated that at the location of the closure assembly 34, the tapes 18 and 20 are subjected to repeated maximum pull each time the hook and eye are engaged and disengaged, for which reason the features of the invention hereinbefore described are significant in producing a more durable and neater slide fastener installation.

While a specific embodiment and exemplary installation of the invention has been described in some detail, it is to be understood that changes in design and construction may be made without departing from the principles of the invention. Therefore, the invention is not to be construed as restricted to the foregoing description except as defined in the claims which follow.

I claim:

1. In a garment having overlapping edge portions adapted to be drawn together by edge fastener means including a slider movable to a closed end position, said fastener means being secured to said overlapping edge portions by a pair of edge fastening tapes; a combined end closure and slider stop assembly disposed in abutting relation to said slider at said closed end position thereof to prevent separation and disassembly of the slider from the fastener means, comprising, an eye member secured in adjusted position to one of said edge fastening tapes and projecting toward the other of said tapes, hook means secured to the other of said edge fastening tapes in alignment with said eye member, attachment means projecting from said hook means toward said one of the tapes beyond said other of the tapes, and means for securing the attachment means directly to an overlapping edge portion of the garment independently of and in spaced relation to said other of the edge fastening tapes to prevent separation of said tapes from the garment adjacent the closed end position of the slider.

2. The combination of claim 1, wherein said hook means includes a flat portion, a pair of prongs projecting from one side of said flat portion for securing the hook means to said other edge fastening tape, a hook portion projecting from the flat portion on a side thereof opposite said prongs, said attachment means being disposed in the plane of said flat portion on opposite sides of the hook portion.

3. The combination of claim 2, wherein said attachment means comprises a pair of lugs formed integral with said hook means and projecting in a direction away from said other edge fastening tape in overlapping relation to said eye member, and means formed at remote

5

10 terminal ends of said lugs for tacking the lugs directly to the garment material.

4. The combination of claim 1, wherein said attachment means comprises a pair of lugs formed integral with said hook means and projecting in a direction away from said other edge fastening tape in overlapping relation to said eye member, and means formed at remote terminal ends of said lugs for tacking the lugs directly to the garment material.

15

5. In an edge fastener assembly for garments mounted by flexible tapes and having terminal end closure means secured to the tapes; said closure means having an eye member secured to one of the tapes and hook means secured to the other of the tapes, said hook means comprising, a flat portion disposed in bridging relation between said tapes, attachment means projecting from said flat portion beyond said other of said tapes for securing the hook means to the garment independently of and in spaced relation to said tapes, and means for 20 tacking the attachment means to the garment at spaced locations substantially in the plane of said flat portion overlapping said one of the tapes,

25

6. The combination of claim 5, wherein said attachment means comprises a pair of lugs projecting from the hook means in the plane of said flat portion and in overlapping relation to the eye member to which the tacking means is secured.
